UNITED STATES PATENT OFFICE.

JAMES M. BUTCHER, OF CHICAGO, ILLINOIS, ASSIGNOR TO WILLIAM L. ROHRER, OF CHICAGO, ILLINOIS.

ALARM.

1,287,871.

Specification of Letters Patent.

Patented Dec. 17, 1918.

Application filed July 12, 1917. Serial No. 180,065.

To all whom it may concern:

Be it known that I, JAMES M. BUTCHER, a citizen of the United States, and resident of Chicago, in the county of Cook and State of Illinois, have invented certain new and useful Improvements in Alarms, of which the following is a specification.

This invention relates to alarms.

One object is to insure in a novel manner 10 a continuous signal action of an alarm.

Another object is to provide an alarm mechanism adapted to meet the various requirements for successful use.

These and other objects are accomplished 15 by providing an alarm mechanism including signal means, means normally preventing signaling action thereof, and means operatively connected with said last mentioned means whereby continuous signaling action 20 of said signal means is caused to result.

The invention is illustrated on the accompanying sheet of drawings, in which,

Figure 1 is a fragmentary sectional view 25 of relatively movable upper and lower windows equipped with my alarm;

Fig. 2 is a plan view of the same, parts being in section, and

Fig. 3 is a fragmentary detail view, parts 30 being in section, of the alarm mechanism taken in the plane of line 3—3 of Fig. 2.

The various novel features of the invention will be apparent from the following description and drawings, and will be particularly pointed out in the appended claims.

35 While my invention is not necessarily limited to a burglar alarm, I choose to illustrate the same in connection with such a use, and to show it particularly in connection with a window construction including upper 40 and lower windows 10 and 11, respectively, which are relatively movable with respect to each other.

One of the objectionable features in connection with burglar alarms, especially those 45 applied to windows, is that a signaling action of the alarm is not continuous, or at least cannot be relied upon to be continuous. This is one of the disadvantages which I have overcome by means of my novel alarm 50 mechanism. Again, since it is desirable to provide for a wide range of location, maximum facility for attachment and minimum defacement of the relatively movable structures that support the alarm and coact with 55 its releasing elements, application of the

alarm is preferably through the medium of a mounting to which the alarm proper may be secured and which is itself readily attached to one of the structures in position to thrust the releasing element into frictional 60 coaction with the other structure; and since building structures greatly vary in dimensions and it is not always convenient to attach an alarm with accuracy of location, the mounting is composed of two members, one 65 the attaching support and the other the alarm carrier interlocked with the attaching support but longitudinally slidable thereon, with means for arresting it at any adjustment; and the releasing element is presented 70 in position to have its frictional and actuating impingements developed through and regulated by said longitudinal adjustment. Preferably, this releasing element is located upon the carrier member of the mounting 75 independently of the alarm proper in position to be thrust against the coacting relatively moving structure on the one hand, and to receive the control element of the alarm proper on the other hand.

I prefer to mount my alarm 12 on the upper sash member 13 of the lower window, and have the same adjustable with respect to the lower window 11, and also with respect to the upper window 10. To this end 85 I have secured to the sash member 13 a mounting comprising an attaching, supporting and guiding member 14, upon which the alarm proper is slidably mounted. The alarm proper may be secured to the member 90 14 in any adjusted position by means of a suitable lock screw or member 15, which is carried by and passes through a carrier preferably formed by a metal strip 16 confined by and sliding longitudinally upon 95 the attaching member, and to which the body 17 of the bell, which in this case is the alarm, is secured in any suitable manner. The working parts of the bell include any suitable mechanism. I have here shown various 100 gears to which is operatively connected a ratchet wheel 18 which cooperates with the pawl end 19 of a lever 20, having at its free end a bell clapper or hammer 21, which is rapidly vibrated into and out of engagement with the removable cover 22 of the bell for giving the alarm. This lever 20 is pivotally mounted at 23 near its pawl end. Normally the pawl 19 is held in engagement 105 with the ratchet wheel 18 to prevent move- 110

2

ment thereof and also to prevent signaling action of the alarm by a resilient L-shaped member 24, one leg of which is suitably anchored to a stationary part 25, and the lower end of the other leg of which passes over the outer side of the lever 20 and is provided with a plunger 26 which extends outwardly through an opening 27 in the body of the bell. The essential features here are an alarm or signal which will maintain its alarm emitting function, once the same is initiated, and a control element through which to initiate action in the alarm. Combined with these features, the invention contemplates a release element acting upon the alarm through the control element whenever relative movement takes place between the two structures of the opening (window, door, or the like) to be guarded. The essential features of this release element are that it is adapted to be actuated through frictional impingement against the normal surface of wood, glass, metal or other material of the coating structure, without the interposition of gearing, covering or other special surface-shaping attachments on the latter; also that said releasing element shall be so presented as to have its impingement developed by the longitudinal adjustment of the carrying member of the mounting so that various dimensions of the coating structures may be compensated for, and pressure may be regulated, in addition to moving the alarm to and from operative positions. Preferably this releasing element has its bearings directly upon the sliding carrier of the mounting so that the alarm is brought under its control by merely attaching the alarm to said slide.

According to the preferred method of realizing this part of the invention, a recessed portion 28 of a lever 29 engages the outer end of the plunger 26 to normally hold the resilient member 24 against the lever 20 to hold the pawl 19 and the ratchet wheel 18 stationary. Under such conditions the alarm is prevented from sounding. The lever 29 is provided with a circular portion eccentrically mounted upon a pin 31 extending between side plates 32 preferably struck up from the metallic strip 16. This circular portion is provided with teeth or serrations 33 or other suitable friction surface which normally engage with a member, in this case the window 10, which is movable relatively to the other member, which in this case is the window 11, upon which the alarm proper is mounted. The friction surface 33 on the lever 29 permits operative contact with any part of the window sash or glass without the necessity for an attachment on the other sash.

In Fig. 1 it will be noted that the alarm is mounted upon the window member 11 and secured in such an adjusted position

with respect thereto by the set screw 15 that the toothed portion 33 of the lever 29 is in engagement with the window 10. With this arrangement of parts it is apparent that if the lower window is raised or the upper window lowered, or if there is any relative movement whatsoever between the upper and lower windows, the lever member 29 will be rotated in a clockwise direction carrying the detent portion 28 thereof beyond the plunger 26, the flat portion 34 of the lever member 29 swinging around and into a position adjacent the plunger 28 and permitting the latter to move outwardly thereby reducing the pressure upon the lever 20 and permitting the ratchet wheel 18 to rotate under the influence of its actuating spring to vibrate the hammer 21 against the cover of the bell to sound the alarm. It is seen therefore that upon a slight clockwise rotation of the lever member 29 the bell hammer is not only liberated but is permitted to be vibrated for sounding the alarm.

It is to be noted that under these conditions the alarm will continue to sound until the spring is run down, for even though the windows should be given a relative movement which would have a tendency to throw the lever control member 29 back into its normal position, such return action is impossible. The control lever 29 can be returned only by hand; that is by pushing the lever in a counter-clockwise direction, as shown in Figs. 1 and 3. When this is done the resilient member 24 is pressed back into its normal position to hold the pawl and also the bell hammer 21, respectively.

In this particular case I have shown the control member in engagement with the upper window. It may, however, be in engagement with the window jamb or in engagement with any other part where there is relative movement between that part and the window member carrying the alarm proper. However, I have shown in the drawings the manner of mounting which I prefer.

It is evident that there may be various modifications of the invention herein particularly shown and described, and it is my intention to cover all such modifications which do not depart from the spirit and scope of the invention as set forth in the following claims.

I claim:

1. In alarm mechanism, the combination of signal means adapted to give a continuous signal action, trip means normally preventing signaling action thereof, and an eccentrically mounted member having a friction surface and operably associated with said trip means whereby the trip means may be acted upon to permit continuous signaling action of said signal means.

2. In alarm mechanism, the combination

- of signal means including a movable bell hammer, which when liberated is actuated continuously, means for normally holding the bell hammer stationary, and eccentrically mounted means having a friction surface operatively connected with said holding means for liberating the bell hammer.
3. In alarm mechanism, the combination of signal means including a lever having a bell hammer, a resilient member normally arranged over said lever for holding the hammer stationary, and a movable member operatively connected with said resilient holding member for liberating the hammer to permit the same to give an alarm, said movable member having a friction surface for operably engaging any portion of a moving element.
4. In alarm mechanism, the combination of signal means including a bell hammer capable of continuous action when liberated, a resilient member associated with said hammer member and having a laterally extending projection, and a control member engageable with said projection for normally holding the bell hammer stationary, said control member having a friction surface for operably engaging a moving element and when actuated adapted to liberate said bell hammer.
5. In alarm mechanism, the combination of signal means including a bell hammer capable of continuous action when liberated, a resilient member associated with said hammer member and having a laterally extending projection, and an eccentrically mounted control member engageable with said projection for normally holding the bell hammer stationary, said control member when actuated liberating said bell hammer, said control member having a friction surface for operably engaging a moving element.
6. In alarm mechanism, the combination of a bell having a body portion with an opening therein, a lever having a bell hammer thereon, a resilient member engageable with said lever and having a projection extending through said opening, and a control member normally engaging said projection to press the resilient member against said lever to hold the hammer stationary and operable to liberate said hammer to sound an alarm, said control member having a friction surface for engagement by a moving element.
7. In combination, relatively movable window members, and an alarm connected to one of said members and having means frictionally operable by the other member to cause a continuous signaling action of the alarm upon a relative movement of said window members and even after said members are returned to their normal positions.
8. In combination, relatively movable window members, and an alarm mechanism
- mounted on one having means normally for preventing signaling action thereof, said alarm mechanism having means frictionally operable by the other of said window members for causing a continuous signaling action of said alarm mechanism upon a relative movement of said window members and even after said members are returned to their normal positions.
9. In combination, upper and lower window members having a relatively movable action with respect to each other, and alarm mechanism secured to said lower window member and having means normally engaging with the upper window member and being frictionally operable by the latter for causing a continuous signaling action of said alarm mechanism upon a relative movement of said window members and even after said members are returned to their normal positions.
10. In combination, relatively movable members, and alarm mechanism adjustably mounted on one of said members and being frictionally operable by the other for giving a continuous signal upon relative movement of said members and even after said members are returned to their normal positions.
11. In combination, signal means and a support, the support adapted to be fixed to a window sash, said signal means being movably mounted in the support, a trip carried by said signal and operably connected thereto to normally prevent signaling action thereof, said trip having a friction surface for engaging a window pane, whereby the trip may be actuated to permit continuous signaling action of said signal means when said window pane is moved relatively to said signal means.
12. In an alarm device, for mounting upon the one and coacting with the other of two structures between which there is relative movement; an alarm, a mounting therefor comprising an attaching support adapted to be secured upon the one of said structures, an alarm-carrier interlocked with said support but having adjustment thereon, a locking device for fixing the carrier in its adjusted position, and a frictionally actuated alarm releasing element moved to and from a surface of said other structure by said adjustment and presented for frictional actuating impingement substantially in the direction of said adjustment.
13. In an alarm device, for mounting upon the one and coacting with the other of two structures between which there is relative movement; an alarm, a mounting therefor comprising an attaching support adapted to be secured upon the one of said structures, an alarm-carrier interlocked with said support but having adjustment thereon, a locking device for fixing the carrier in its adjustments, and a frictionally actuated alarm

releasing element, mounted on the carrier independently of the alarm, in position to be moved to and from a surface of said other structure by said adjustment and presented 5 for frictional actuating impingement substantially in the direction of said adjustment.

14. In an alarm device, adapted for mounting upon the one and coacting with 10 the other of two structures between which there is relative movement; a continuous action alarm, a mounting therefor comprising an elongated attaching support adapted to be secured upon the one of said structures in position presented longitudinally toward

the other of said structures, an alarm carrier interlocked with said attaching support but sliding longitudinally thereon for adjustment to and from the surface of the said other structure, a locking device for fixing 20 the adjustment between said support and carrier, and a frictionally actuated rotary releasing element moved to and from said surface of the other structure by said adjustment and presented to have its frictional 25 actuating impingement substantially in the direction of said adjustment.

Signed at Chicago, State of Illinois, this 7th day of July, 1917.

JAMES M. BUTCHER.
